UNITED STATES PATENT OFFICE.

CHARLES B. MAXSON, OF WESTERLY, RHODE ISLAND.

SHEET-DELIVERY APPARATUS FOR PRINTING-MACHINES.

SPECIFICATION forming part of Letters Patent No. 351,991, dated November 2, 1886.

Application filed December 29, 1885. Serial No. 187,048. (No model.)

To all whom it may concern:

Be it known that I, CHARLES B. MAXSON, a citizen of the United States, residing at Westerly, in the county of Washington and State of Rhode Island, have invented new and useful Improvements in Sheet-Delivery Apparatus for Printing-Machines, of which the following is a specification.

The object of this invention is to produce an improved sheet-delivery apparatus for printing presses, and especially cylinder-presses, whereby the sheet may be delivered with its freshly-printed side upward and without being touched by any part of the apparatus. This object I have accomplished, as herein-after described, and illustrated in the accompanying drawings, in which—

Figure 1 is a side elevation of the impression-cylinder of a printing-press constructed according to my invention. Fig. 2 is a plan or top view of the same. Fig. 3 is a sectional view of a portion of the impression-cylinder on a larger scale than the previous figures. Fig. 4 is a similar view of a modification.

Similar letters indicate corresponding parts.

In the drawings, the letter A designates a portion of the press-frame constructed to form the bearings for the impression-cylinder B and the support for the type-bed. (Not shown in the drawings.) In a suitable cavity, D, of this cylinder are arranged the usual grippers, B³, for holding the sheet to be printed on the cylinder, those grippers being opened and closed by trip-pins B⁴ acting on a cam, B⁵, Fig. 2, mounted upon the end of the gripper-shaft B⁶. The cylinder makes two revolutions during a complete traverse of the bed in both directions, and to adapt the grippers B³ to such motion of the cylinder the trip-pins B⁴ are alternately thrown in and out of action by a cam, B⁷, the whole constituting a press of well-known construction.

To raise the leading edge of the sheet from the cylinder after it has been printed and released by the grippers, a series of sheet-lifters, L, are mounted on a rock-shaft, L', which has its bearings in the frame A. From the rock-shaft extends a lever, L², which engages with a cam, L³, for imparting the proper motion to the sheet-lifters. By referring to Fig. 1 it will be seen that the cam L³ is of such a form that

the sheet-lifters are permitted to drop immediately before the grippers are opened, so that said sheet-lifters are in position to pass beneath the leading edge of the sheet, and as soon as this has taken place they are raised, so as to clear the impression-cylinder and to support the sheet during its passage to the delivery-tapes M.

For the purpose of permitting the tips of the sheet-lifters to pass without fail beneath the leading edge of the sheet, I have provided the clamping-support of the grippers B³ with recesses n. In the example shown in the drawings the clamping-support of the grippers is formed by the tympan-fingers N. These fingers are mounted on a shaft, N', extending through the cavity D in the impression-cylinder, and they serve to clamp one end of the tympan-sheet N² against the breast of the cavity, (see Fig. 3,) being retained in their locking position by a spring-lever, N³, which extends from the shaft N', and is retained by a pin, N⁴, projecting from the cylinder B. (See Figs. 1 and 2.) The opposite end of the tympan-sheet is secured to a shaft, N⁵, which extends through a cavity in the cylinder, and is retained in position by a ratchet wheel and pawl, or by other suitable means, as commonly practiced in printing-presses. The upper ends of the tympan-fingers N are flush, or nearly so, with the surface of the cylinder, and they form the support for the leading edge of the sheet. The recesses n are inclined and correspond in position to the sheet-lifters L, so that as the cylinder revolves toward them the tips of said sheet-lifters will slide up on the inclined faces of the recesses and pass beneath the leading edge of the sheet. The tympan-fingers may, however, be reduced in length, so that they are inside the circumference of the cylinder and form no part of the support of the sheet. In this case the recesses n will be made into the breast of the cavity D, and portions of the tympan-sheet have to be cut away to permit the tips of the sheet-lifters to pass beneath the leading edge of the sheet. (See Fig. 4.)

What I claim as new, and desire to secure by Letters Patent, is—

1. The combination, with the impression-cylinder, the cylinder-grippers, and the clamping-support for the gripper-tips, of sheet-lift-

ers, and of recesses formed in the clamping-support, substantially as shown and described.

2. The combination, with the impression-cylinder, the cylinder grippers, and the tympan-fingers N, extending up flush, or nearly so, with the cylinder of sheet-lifters, and of recesses formed in the tympan-fingers.

In testimony whereof I have hereunto set my hand and seal in the presence of two subscribing witnesses.

CHARLES B. MAXSON [L. S.]
